UNITED STATES PATENT OFFICE

ALFRED A. CONKLIN, OF WEST HAVEN, CONNECTICUT

WRENCH FOR VALVE-SEATS AND THE LIKE

Application filed March 20, 1931. Serial No. 523,960.

This invention relates to an improvement in wrenches and particularly to an improvement in wrenches for installing and removing valve-seats or port-plugs of various types such as those employed in steam-turbines, etc.

Valve-seats, especially those through which hot corrosive fluids flow, such as steam, become corroded or "frozen" in place and are extremely difficult to remove without injuring or destroying the same, particularly when they are in relatively inaccessible positions.

I am aware that heretofore efforts have been made to provide special wrenches for the removal of valve-seats, but such wrenches, to be effective, have required the formation of threads in the flow-passages of the valve-seats in order to provide an anchorage to positively hold the wrench in place. The formation and the mere presence of threads in the flow-passage of a valve-seat is objectionable for obvious reasons, among which may be mentioned the fact that such threads weaken the relatively-thin walls of the valve-seat and interfere with the smooth flow of high velocity steam, etc., through the axial passage therein.

The main object of my present invention is to provide a simple, rugged and convenient wrench which may be firmly anchored to the valve-seat for turning the same without injury thereto and without requiring the formation of threads therein.

With the above and other objects in view as will appear from the following, my invention consists in a wrench for valve-seats and the like having certain details of construction and combinations of parts as will be hereinafter described and particularly recited in the claims.

In the accompanying drawings:

Fig. 1 is a view in side elevation of a valve-seat wrench embodying my invention and shown as anchored to a valve-seat for the removal thereof;

Fig. 2 is a view thereof in central longitudinal section, taken on the line 2—2 of Fig. 1;

Fig. 3 is a view in side elevation of the anchoring-sleeve;

Fig. 4 is an end view thereof; and

Fig. 5 is a view in side elevation of the draft-rod.

In the particular embodiment of my invention herein chosen for illustration, I employ a wrench-body 10 formed with a longitudinal axially-arranged bore 11 and provided at its upper end with a polygonal head 12 for the purpose as will hereinafter appear, and provided at its inner end with a plurality of downwardly-extending coupling-lugs 13 separated by transverse cuts 14 and adapted to enter and interlock with upwardly-opening notches or sockets 15 formed in the upper face of a valve-seat 16, which may assume a variety of forms and which, as herein shown, is provided with an upwardly- and outwardly-tapering axial flow-passage 17 and a downwardly-extending externally-threaded shank 18 screwed into an internally-threaded passage 19 in a valve-housing 20. The valve-housing 20 may assume a variety of forms but, as shown, is formed with a pocket or recess 21 at the bottom of which the valve-seat 16 already referred to is installed.

The downwardly-extending coupling-lugs 75 of the wrench serve to couple the structure with the valve-seat 16 for concurrent rotation, but it so happens that when the said valve-seat is corroded in place and, therefore, very difficult to turn, that the coupling-lugs 13 aforesaid are apt to ride out of the notches 15 in the upper face of the said valve-seat.

To prevent the coupling-lugs 13 from riding out of the coupling-notches 15, as above described, I install in the longitudinal bore 11 of the body 10, an anchoring-sleeve 22 which is formed near its lower end with a relatively-wide annular peripheral groove 23. The lower end of the said sleeve 21 is formed with four (more or less) longitudinal slots 24 which extend from its extreme lower end upward to a point just below the upper terminus of the annular groove 22 before referred to and result in the production of four (more or less) resilient anchoring-fingers 25 each of which is provided, as shown, with an upwardly-facing anchoring-shoulder 26, adapted to engage the lower edge of the shank 18 of the valve-seat 16 around the ad-

jacent end of the axial bore 17 thereof, as clearly shown in Fig. 2 of the drawings.

To maintain the anchoring-shoulders 26 in "hooked" engagement, so to speak, with the under-face of the shank 18 of the valve-seat and to simultaneously positively seat the coupling-lugs 13 in the coupling-notches 15 of the said valve-seat, I employ a draft-rod 27 which is slidably mounted within the axial bore 28 in the anchoring-sleeve 22 before referred to, and is formed at its lower end with a shank 29 of reduced diameter terminating in an upwardly- and inwardly-tapering conical head 30, the sloping surface of which 10 engages with a correspondingly-tapered surface 31 formed upon the lower inner edges respectively of each of the anchoring-fingers 25.

The upper end of the draft-rod 27 before referred to is externally-threaded as at 32 and passes upward through a relatively-thick bearing-disk 33 and having applied to its upper end a nut 34, the under-face of which latter bears against the said bearing-disk 33.

With the parts engaged with the valve-seat as shown in Figs. 1 and 2 and the nut 34 tightly screwed down, the flexible anchoring-fingers 25 will be forced outward so as to hook their anchoring-shoulders beneath the lower end of the said valve-seat and at the same time, the wrench-body 10 will be drawn downward so as to positively crowd the coupling-lugs 13 projecting downwardly from the lower end thereof into the coupling-notches 15 of the said valve-seat so that when a tool is applied to the polygonal head 12 of the wrench-body in such manner as to provide a high turning leverage, the said coupling-lugs will be positively prevented from 30 riding out of the coupling-notches in the valve-seat, so that despite the fact that the said seat may be corroded or "frozen" in place, it can in most instances be forced free and unscrewed for replacement or regrounding.

It will be understood by those skilled in the art that my invention may assume varied physical forms without departing from my inventive concept and I, therefore, do not 50 limit myself to the specific embodiment herein chosen for illustration, but only as indicated in the appended claims.

I claim:

1. As a new article of manufacture, a wrench for valve-seats and the like, consisting of a body-member having a longitudinal passage extending therethrough from end to end and formed at its lower end around the said passage with one or more downwardly-projecting coupling-lugs adapted to enter upwardly-opening coupling-sockets in a valve-seat for turning the same; an anchoring-sleeve located in the longitudinal passage in the said body-member and provided at its lower end with a plurality of radially-yielding

fingers, each provided with an upwardly-facing anchoring-shoulder adapted to engage the lower end of a valve-seat; a draft-rod installed in the hollow interior of the said anchoring-sleeve and provided at its lower end with inclined means for outwardly deflecting the yielding fingers of the said sleeve and exerting an upward draft thereupon; means engaging the upper portions respectively of the said draft-rod and body-member to simultaneously exert an upward draft upon the former and a downward force upon the latter to positively seat the downwardly-projecting coupling-lugs thereof in the coupling-sockets of a valve-seat.

2. As a new article of manufacture, a wrench for valve-seats and the like, consisting of a body-member having a longitudinal passage extending therethrough from end to end and formed at its lower end around the said passage with one or more downwardly-projecting coupling-lugs adapted to enter upwardly-opening coupling-sockets in a valve-seat for turning the same; an anchoring-sleeve located in the longitudinal passage in the said body-member with capacity for axial sliding movement therein and formed at its lower end with a plurality of integral flexible fingers, each provided with an upwardly-facing anchoring-shoulder adapted to engage the lower end of a valve-seat; a draft-rod installed in the hollow interior of the said anchoring-sleeve and provided at its lower end with inclined means for outwardly deflecting the flexible fingers of the said sleeve and exerting an upward draft thereupon; means engaging the upper portions respectively of the said draft-rod and body-member to simultaneously exert an upward draft upon the former and a downward force upon the latter to positively seat the downwardly-projecting coupling-lugs thereof in the coupling-sockets of a valve-seat.

In testimony whereof, I have signed this specification.

ALFRED A. CONKLIN.
